UNITED STATES PATENT OFFICE

2,518,398

APPARATUS FOR SPINNING PIPE

Albert L. Stone, Palos Verdes Estates, Calif., assignor, by mesne assignments, to Standard Oil Development Company, Elizabeth, N. J., a corporation of Delaware

Application August 22, 1946, Serial No. 692,203

4 Claims. (Cl. 255—35)

1

The present invention is directed to a device for rotating an elongated body. In its more specific aspects, the present invention is directed to a device for rotating a body having a cylindrical surface such as a stand of pipe with the axis of the body vertical and the body supported and rotated simultaneously by the aforesaid device.

In some commercial operations it is desirable to provide a device capable for rotating an elongated body through a number of revolutions. As an example of such an operation may be mentioned the withdrawal of drill stem from a borehole and the running of drill stem into a borehole where a completed string of pipe of many thousands of feet in length is to be assembled by securing together relatively short lengths of pipe through screw thread connections. It is conventional practice at the present time when withdrawing drill pipe from the borehole to disconnect portions thereof, commonly designated as stands, as the drill stem is withdrawn from the borehole to expose a stand at the surface of the hole which is then removed. The unscrewing of pipe exposed at the surface from the remainder of the drill stem is commonly accomplished by the use of tongs to break the joint and subsequently the use of a rope or chain wrapped around the pipe to spin the pipe and disconnect the screw joint. Similarly, in making up the joint it is common practice to spin the stand being added by means of a rope or chain and then make the joint tight with tongs.

In the method of handling pipe disclosed in my copending application entitled "Method for Stacking Drill Pipe," Serial No. 690,944, filed August 16, 1946, the stands of drill pipe being disconnected from the drill stem are raised by a force supplied to the lower end of the drill stem until the pin thread of the stand clears the box thread at the top of the drill stem, the disconnected stand then moved over from the center of the derrick to leave a clear path for the traveling blocks and the weight of the disconnected stand then supported by elevators attached to the top of the stand. In carrying out this procedure, it is convenient to provide a means capable of spinning the stand of drill pipe being disconnected and also capable of supporting the weight of the disconnected stand of pipe at its lower end.

It is an object of the present invention to devise a means adapted to be engaged with and to be disengaged from an elongated cylindrical body and which is capable of applying a rotational force to the body.

Another object of the present invention is to

2

devise a means adapted to be engaged with an elongated cylindrical body having its axis vertical, to rotate the body and to support the weight of the body.

Another object of the present invention is to devise a means having a rotatable annulus in segmental form which annulus may be secured around a cylindrical body and released from a cylindrical body with means for applying a rotational force through the annulus to the body and means for supporting the weight of the body through the annulus.

Still another object of the present invention is to devise an apparatus having a segmental annulus adapted to embrace a cylindrical body and to be disengaged from the cylindrical body and arranged to rotate the cylindrical body through a cycle of predetermined length and including more than a full revolution.

The device of the present invention may be described briefly as involving a split annulus arranged in jaws which may be operated to position a length of pipe within the annulus and which may be closed whereby the pipe is engaged with the annulus for rotation therewith; a prime mover is arranged for rotating the annulus through a cycle including more than a complete revolution and means are provided for stopping the annulus at exactly the same position in the jaws when the cycle is completed. This portion of the device will be hereinafter referred to as the spinner element. The device of the present invention also includes a hinged arm arranged for supporting the spinner whereby it may be given movement horizontally and a column supporting a hinged arm whereby the arm and spinner may be moved vertically.

The invention of the present application will now be described in greater detail in conjunction with the drawing in which—

Fig. 1 is a top plan of an embodiment of the present invention;

Fig. 2 is a view taken along line II—II of Fig. 1;

Fig. 3 is a view taken along line III—III of Fig. 1;

Fig. 4 is a view taken along line IV—IV of Fig. 1;

Fig. 5 is an elevation of a portion of the embodiment of Figs. 1 to 5;

Fig. 6 is another embodiment of means for holding pipe which may be substituted for the corresponding portion of the assembly shown in Figs. 1 to 4, inclusive;

Fig. 7 is a view taken along line VII—VII of

Fig. 6;

Fig. 8 is a view taken along line VIII—VIII of Fig. 6;

Fig. 9 is a fragmentary view showing another embodiment of the annulus and slip arrangement suitable for use in the spinner; and

Fig. 10 is a fragmentary view showing in greater detail a portion of the apparatus of Fig. 9.

Turning now specifically to the drawing and first to the embodiment of Figs. 1, 2, 3, and 4, an arm A is hinged to arm B through a suitable hinge joint C and the arm B in turn is secured to column D.

Arm A carries mechanism for gripping a cylindrical body such as a stand of pipe in a derrick with its axis vertical and for rotating the pipe through a cycle of predetermined length and for releasing said pipe. The hinged joint C allows the arm members A and B to be lengthened or shortened as desired. Column D is variable as to length and also allows the arm B to be swung horizontally if desired.

Taking up first arm A, it will be seen that structural member 11 has one end secured to hinge C and the other end defining a portion of a jaw or clamp. The other portion of the jaw is defined by member 12 which is secured to member 11 by pin 13.

Members 11 and 12 cooperate to define a mounting means for a split annulus or ring consisting of halves 14 and 15. The halves 14 and 15 are provided with a lining 9 which is formed of an elastic material, such as rubber, and is adapted to grasp a joint of pipe embraced by the split ring. Halves 14 and 15 and lining 9 are of such dimensions that when the two halves form a ring the lining will grip a joint of pipe with sufficient friction to hold the weight of the pipe. At the same time the lining is sufficiently free so that when a joint of pipe is being connected and is made up, continued rotation of the split ring will cause lining 9 to slip and allow the split ring to rotate with respect to the joint of pipe.

When the two halves 14 and 15 are placed together to form a ring, the outer surface thereof defines an upper screw thread 16 terminating at its upper end in shoulder 17 and a lower screw thread 18 terminating at its lower end in shoulder 19. By the screw threads 16 and 18 the two members 14 and 15 define a gear 20. When members 11 and 12 are clamped together they similarly define an upper thread cooperating with screw thread 16 and a lower thread cooperating with screw thread 18.

A hole is drilled in member 14 arranged for receiving a pin 21 and a similar hole is drilled in member 15 and arranged to receive a pin 22. It will be seen that the pins 21 and 22 are parallel to the axis defined by the split ring member consisting of halves 14 and 15. Pins 21 and 22 are slightly longer than are the members 14 and 15 and are engaged in a circular groove 23 defined by members 11 and 12 and a lower groove 24 similarly defined by members 11 and 12. A stop member 25 is secured to arm A for engagement with shoulder 17 of the split ring when the split ring is in its uppermost position and a stop 26 for engaging with shoulder 19 when the split ring is in its lowermost position.

It will be evident that stop members 25 and 26 cooperate with screw thread 16 to define the limits of rotation of the split ring. Stop 25 insures that when the split ring is in its uppermost position portion 14 is embraced within member 11 and portion 15 is embraced within

member 12. Inasmuch as the shoulders 25 and 26 cooperating with shoulders 17 and 19 of the screw threads insure that the halves will stop as described heretofore, pin 21 will always be within in the portions of grooves 23 and 24 defined by member 11 and pin 22 will be within the portions of grooves 23 and 24 defined by member 12 when the split ring is either in its uppermost or lowermost position.

Jaw member 12 is arranged to pivot on pin 13 after the split ring consisting of members 14 and 15 has been rotated until it reaches the limitation of travel, that is after rotating in one direction until shoulder 17 strikes shoulder 25 or after rotating in the other direction until shoulder 19 strikes shoulder 26. In either of these positions two halves of the split ring will be exactly within members 11 and 12 and jaw 12 may then be pivoted open on pin 13 without exposure of thread 16 and when the jaw member 12 is returned to its closed position the two halves 14 and 15 will occupy the same position they were in before the jaw member was opened.

It will be understood that the means for rotating the split ring may be any suitable prime mover. In the drawing a prime mover is indicated by a showing of housing 27 secured to arm member 11 with a drive shaft 28 projecting from the housing. In order to simplify the description, the prime mover is indicated only schematically. Shaft 28 is supported by bearings 29 and 30 and has a gear 31 mounted thereon for rotation therewith. Also carried by arm member A is a shaft 32 having its axis of rotation parallel with that of shaft 28 and also with the axis of rotation of the split ring consisting of members 14 and 15. Shaft 32 is journaled to member 11 by bearings 33 and 34 and has mounted thereon a gear 35 arranged to mesh with gear 31 and with gear 20 whereby power is transmitted from gear 31 to the split ring member. It will be noted that the teeth of gear 35 are considerably longer than the teeth of gear 20 thereby allowing gear 20 to be moved longitudinally with respect to gear 35 while maintaining the two gears in engagement. In other words, the rotation of the split ring causes longitudinal as well as rotational movement to be imparted to the split ring but upon such longitudinal movement the teeth of gear 20 slide along the teeth of gear 35 insuring that power is continuously transmitted to the split ring element as it moves longitudinally.

Releasable locking means for maintaining member 12 in position with its free end in contact with member 11, thereby clamping split ring members 14 and 15 firmly in position, is provided by extension 37 defining a cam surface 38 adapted to cooperate with a similar surface defined by wedge member 39. A hydraulic cylinder 40 is mounted on member 11 and has slidably mounted therein a piston 41 attached to piston rod 42 which in turn is secured by suitable means, such as pin 43 to wedge member 39. At the end of cylinder 40 is arranged an annulus 44 which embraces the piston rod and serves as a retainer for spring 45 carried by the piston rod. It will be seen that cylinder 40 and piston 41 cooperate to define a chamber having an inlet 46 which may be connected to a suitable source of hydraulic fluid under pressure, not shown.

Jaw member 12 may be clamped tightly in position by imposing a desired hydraulic pressure against piston 41 by applying the pressure

through inlet 46. The application of pressure in this manner forces wedge member 39 tightly against surface 38 of member 12 and thereby clamps the free end of this member tightly against member 11. When it is desired to release member 12 this may be done by releasing pressure at inlet 46 which in turn allows spring 45 to return the piston 41 toward inlet 46 and withdraw wedge member 39 out of contact with surface 38.

When engaging the spinner with a joint of pipe it is necessary to close jaw member 12 manually before it is locked in place by wedge member 39; similarly, when opening jaw member 12 it is necessary first to unlock it by withdrawing wedge member 39 from contact with surface 38 and then open the jaw manually. For convenience in this manual operation, jaw 12 is provided with a handle 8 which may be grasped by an operator in carrying out the opening or closing operation.

Arm B consists of a laterally extending member 50 which in turn has one end secured to hinge joint C and the other secured to column D. Hinge joint C consists of a tubular member 51 having its lower end secured to member 50 of arm B. Bearing members 52 and 53 are mounted on member 51 and are retained in position by retaining rings 54 and 55, respectively. A tubular member 56 is mounted for rotation about a vertical axis on bearings 52 and 53 and in turn has member 11 of arm A secured thereto. Tubular member 51 is surmounted by a cap member 57.

Column D consists of an inner tubular member 60 having its lower end attached to a base 61 and defining a shoulder 62 on its upper end. Slidably mounted on member 60 is tubular member 63 with its upper end closed by cap 64. It will be seen that the inner surface of member 63 has slightly larger diameter than the outer surface of member 60, thereby defining an annular space between the two members. Member 63 defines a shoulder 65 on the lower end thereof; shoulders 65 and 62 define bearing spaces maintaining members 60 and 63 concentric. A sealing or packing device 66 is mounted on member 60 and a similar sealing device 67 is mounted on member 63. An inlet line 68 is attached to member 63 immediately below sealing member 67 and discharges into the space between members 66 and 67 which is defined between inner surface of member 63 and the outer surface of member 60. By forcing fluid under pressure through inlet line 68 into the space defined between sealing means 66 and 67 heretofore described, the outer tubular member 63 carrying members A, B and C may be forced upwardly and by releasing the pressure through inlet line 68 the weight of members A, B and C allows the assembly to move downwardly with respect to member 60.

It will be seen that member 60 is provided with a circular shoulder 69 which serves to limit the downward movement of tubular member 63. It will be apparent that the vertical movement of member 63 with respect to member 60 will be limited either by the distance separating seal 67 and shoulder 62 or seal 66 and shoulder 65 depending on which distance is the smallest. It will be evident that tubular member 63 is freely rotatable about piston 60, thereby allowing arm B to move angularly in any desired direction relative to base 61.

As heretofore stated, Figs. 1 to 5, inclusive,

disclose an embodiment wherein lining 9 provides the surface to be contacted with the outside circumference of a length of pipe during the spinning operation. This lining must engage sufficiently tightly with the surface of the pipe to allow the pipe to be spun when disconnecting the screw threads connecting the joint with another. It is also desirable for member 9 to exert sufficient friction contact with a joint of pipe that the point may be supported from the assembly and swung over from the center of the borehole to one side thereof.

Another embodiment of a means for engaging with the joint of pipe for spinning it and lifting it which may be substituted for that portion of the device set out in Figs. 1 to 5, inclusive, is set out in Figs. 6, 7 and 8. In this embodiment members 74 and 75 cooperate to form a split ring or annulus corresponding to that formed by members 14 and 15 of the embodiment of Figs. 1 to 5. The split ring, consisting of members 74 and 75, defines an upper screw thread 16 terminating at its upper end in a shoulder 17 and a lower screw thread 18 terminating at its lower end in a shoulder, not shown. Between screw threads 16 and 18, the two members 74 and 75 define a gear 20. Member 74 is provided with a passage for receiving a pin 21 and member 75 is provided with a similar passage for receiving a pin which has been omitted from the drawing for purposes of showing the passage more clearly. The screw threads 16 and 18, gear 20 and rod 21 correspond exactly to that of the embodiment of Figs. 1 to 5 and will not be described further.

The inner surface of the split ring consisting of members 74 and 75 defines a tapered seat 76 arranged for supporting slip members 77 and 78. It will be seen that slip members 77 and 78 define shoulders 89 projecting radially outwardly, said shoulders fitting within grooves defined by members 74 and 75 whereby relative rotary movement between the slip members and the split ring is prevented. Members 74 and 75 also define an inwardly extending ledge 90 which limits the upward movement of slip members 77 and 78 with respect to the split ring. Adjacent the tapered seat the slip members define openings for receiving springs 79 and 80.

Springs 79 serve to raise slip members 77 and 78 away from tapered seat 76 as soon as jaw 12 is opened. They also serve to lift the slip members away from the tapered seat when jaw 12 is in closed position when the pipe embraced by the slips is raised with respect to arm 11 or when arm 11 is lowered with respect to the pipe. With this arrangement, if the thread of the length of pipe being made up in the spinning operation strikes the shoulder before the split ring has gone through its complete cycle, the tapered seat 76 may be lowered, as by allowing column D to lower and the slips are moved away from the tapered seat by the springs. The slips cannot turn with respect to the tapered seat but are loose or free to turn with respect to the pipe so that if the thread of the pipe being made up shoulders before the indexing means has gone through its cycle, the split ring may be released from the pipe by moving the tapered seat downwardly whereby the split ring is free to turn until it has gone through its predetermined cycle. When the split ring is at rest and jaw 12 is open, springs 79 move the slips into contact with ledge 90 and springs 80 move the slips until they strike stops 89. When the device embraces

a length of pipe, the slips contact therewith because they are tilted toward the pipe and because of protruding friction member 81. After jaw 12 has been closed and the pipe moves down with respect to tapered seat 76, the slips are carried downwardly and member 81 is deformed until metal to metal contact is made between the slips and the pipe is seated on tapered seat 76.

When disconnecting joints of pipe, the pipe being rotated does not come into contact with a shoulder and, accordingly, the device spins the pipe until it has gone through its predetermined cycle.

A fragmentary view of another embodiment of a device for contacting the pipe to be spun which may be substituted for corresponding members is shown in Figs. 9 and 10. In Figs. 9 and 10 a member 84 is shown. It will be understood that this member corresponds to members 14 and another member, not shown, similar thereto cooperates therewith to make a complete split ring or annulus. Member 84 differs from member 14 in the manner provided for securing the split ring in position in the mounting means consisting of arm 11 and jaw 12; whereas the embodiments previously described retain the split ring in position by rods fitting into circular grooves defined in members 11 and 12, the embodiment of Figs. 9 and 10 retain the split ring member in position by means of dove-tail-shaped threads. In Fig. 9 member 84 is provided with upper screw threads 86 and lower screw threads 88; these screw threads correspond to threads 16 and 18 of the previously described members except that the threads are dove-tail in section rather than rectangular in section as in the previously described embodiments. It is understood that the upper end of thread 86 terminates in a shoulder, not shown, similar to shoulder 17 with which thread 16 terminates and that thread 88 terminates in a lower shoulder, not shown, similar to shoulder 19 with which thread 18 terminates. Member 84 defines a seat 76 corresponding to the seat 76 of the embodiments shown in Figs. 6, 7, and 8 for receiving a slip member, not shown. It will be seen that in the embodiment of Figs. 9 and 10 the threads defined by member 11, a portion of which is shown, are dove-tailed to cooperate with the dove-tailed threads 86 and 88; it will be evident that in this embodiment the threads defined by member 12, not shown, must also be dove-tailed to cooperate with threads 86 and 88.

The device disclosed in the present application is particularly adapted for handling pipe in connecting and disconnecting the lengths of pipes by screw threads. An example of such operation is the making up of drill stem of casing to be lowered into the hole and the removal of drill stem from the borehole. The device disclosed herein is capable of engaging with a stand of pipe having its axis vertical and when so engaged may move the pipe vertically. It will also be seen that the device disclosed is capable of retaining a length of pipe with its axis vertical and of moving the pipe vertically and horizontally while so retained with said movements being made simultaneously or in sequence therewith. The device is further capable of grasping pipe and of pushing it vertically and horizontally and rotating the pipe with the horizontal, vertical and rotational movements being given the pipe either simultaneously or in any desired sequence.

The device of the present invention is particularly adapted for grasping a stand of pipe to be removed from a drill stem, for spinning the pipe to disengage it from the threaded connection, attaching it to the remainder of the drill stem, for lifting the pipe so that the threads of the pipe clear those of the drill stem and then moving the pipe away from the center line of the derrick. To conduct such an operation, if member 12 is not open it may be released by releasing the pressure in cylinder 40 whereby spring 45 moves wedge member 39 away from surface 38 thereby allowing member 12 to be swung open. Members 14 and 15 may then be engaged on the drill stem and member 12 closed by imposing a pressure in cylinder 40 through inlet 46. This clamps the split ring consisting of members 14 and 16 tightly together. The split ring with the pipe engaged therein is then rotated by prime mover 27. When disengaging pipe the split ring member, consisting of portions 14 and 16, is in its lowermost position with shoulder 19 abutting against member 26 and the member is rotated until it reaches its upper position where it is stopped by contact of shoulder 17 with stop 25. The stand of pipe is then raised so that the threads clear the threads of the lower joint by exerting a suitable super-atmospheric pressure within column 60 of column D. The arms A and B may then be swung to move the stand of pipe away from the center line of the derrick and the pipe then may be released by releasing the pressure in cylinder 40 and opening jaw 12. When making up pipe, the stand of pipe to be attached to the drill stem at its lower end engaged within split ring consisting of halves 14 and 15 the jaw member 12 is then latched in position by imposing the desired pressure on cylinder 40 and the stand of pipe is moved by swinging arms A and B until the lower end of the stand is in position to stab the upper end of the drill stem. In this position the release of pressure within column 60 allows the two arms A and B to be lowered until the joint of pipe is stabbed and the prime mover 27 is then used to rotate the joint of pipe. When beginning the spinning operation in making up pipe, the split ring consisting of elements 14 and 15 is in its uppermost position with shoulder 17 in contact with stop 25, and the split ring is rotated until shoulder 19 engages with stop 26. The jaw 12 may then be released by releasing the pressure in cylinder 40, swinging the jaw open and the device then swung clear of the made up joint of pipe by swinging the arm A on hinged joint C and arm B around column D. It will be evident that the combination of the present application embodies a number of advantageous features. The device is arranged to allow the rotation of a length of pipe through a predetermined number of revolutions and to stop the rotation positively with the members of the combination in fixed position to allow the spinning device to be disengaged from the length of pipe and to be readily engaged with another length of pipe.

The device also provides a means for positively gripping a length of pipe which allows the pipe to be supported, as by its lower end, and to be moved laterally while the axis of the pipe is vertical. It will also be seen that the combination is provided with a locking mechanism which positively locks the device to a length of pipe to be rotated by the device but which is simply released

to allow the device to be disengaged from said pipe.

Having fully described and illustrated the preferred embodiments of the present invention, what I desire to claim as new and useful and to secure by Letters Patent is:

1. A device for rotating a cylindrical body, comprising, in combination, an arm member consisting of a base for mounting a prime mover, an arcuate jaw pivoted to the base, for assuming an open position and a closed position, adjacent portions of the arcuate jaw and the base cooperating to form a cylindrical opening having an interior screw thread on the wall surface thereof when said jaw is in its closed position, a rotating prime mover mounted on the base, a releasable locking means mounted on the arm holding the jaw member in its closed position, a split ring mounted in said cylindrical opening of the arm, and a screw thread on its outer surface engaging with the screw thread of said arm, to allow rotation of the split ring in said arm, an upper stop member mounted on the upper portion of the arm and extending into said circular opening to engage with and to limit positively the rotational movement of said split ring in one direction, a lower stop member mounted on the lower portion of the arm and extending into said circular opening to engage with and limit positively rotational movement of the split ring in the opposite direction, and a train of gears one of which is integral with the split ring operatively connecting the prime mover with the split ring.

2. A device in accordance with claim 1 in which

an elastic lining is secured to the inner surface of each of the sections of said split ring.

3. A device in accordance with claim 1 in which the split ring defines a tapered seat and in which 5 slip members are mounted on the split ring for cooperation with said tapered seat and in which two sets of springs are mounted on said split ring with one end of each spring of one set in contact with the lower surface of a slip and one 10 end of each spring of the other set in contact with a wedge surface of a slip.

4. A device in accordance with claim 1 including 15 a second arm member, a hinged joint connecting the second arm member with said arm member, a tubular vertical member secured to the second arm member, an anchoring member and a vertical column having its lower end attached to the anchoring member and its upper portion fitting slidably within said tubular member.
